UNITED STATES PATENT OFFICE.

JOHN C. McLAUGHLIN, OF EAST ORANGE, NEW JERSEY, ASSIGNOR TO UNDERWOOD TYPEWRITER COMPANY, OF NEW YORK, N. Y., A CORPORATION OF DELAWARE.

COIN-OPERATED TYPE-WRITING MACHINE.

1,309,294.

Specification of Letters Patent.

Patented July 8, 1919.

Application filed November 29, 1916. Serial No. 134,023.

To all whom it may concern:

Be it known that I, JOHN C. McLAUGHLIN, a citizen of the United States, residing in East Orange, in the county of Essex and 5 State of New Jersey, have invented certain new and useful Improvements in Coin-Operated Type-Writing Machines, of which the following is a specification.

This invention relates to a coin-operated 10 machine, and more particularly to means for preventing spurious coins from operating the machine, and for preventing the fraudulent representation, by the user of the machine, that a good coin was used and 15 that the machine failed to operate.

A feature of this invention is the provision of improved means for preventing the use of spurious coins in a time-controlled machine in which the machine is unlocked, 20 so as to be usable when the coin is placed in the machine and is held unlocked for a predetermined length of time, at the expiration of which the machine is automatically locked again.

25 It has been found that in some instances a person, wishing to use the machine without paying therefor, would pretend to insert a coin and then notify the attendant in charge of the machine that a coin had been 30 inserted, but that the machine had failed to operate.

I provide means whereby, after a good coin has been placed in the machine, it will remain in view until the expiration of a 35 predetermined time, when the machine will be locked against further use. Thus, the attendant can always determine for himself whether or not a good coin has been placed in the machine.

40 The mechanism for accomplishing this may comprise a chute-like holder for receiving the coin, open at the bottom and provided with a spring to engage and hold a coin of proper dimension. The coin acts 45 as an interponent between a part actuated by the operator, which may be in the form of an elongated nose adapted to engage the coin, and a part adapted to unlock the machine. If a washer is used, the nose, entering the opening in said washer, fails to effect 50 the proper movement of the coin-holder necessary to unlock the machine. Should a fibrous disk be placed in the holder, said fiber, being engaged only by a small margin

by the coin-holder, would be forced out of 55 the coin-holder.

In order to cause the coin to remain visible while the machine is usable, the coin may be freed from the coin-holder by the movement of the holding spring. When 60 freed from the coin-holder, the coin may drop upon a tray arranged directly behind or beneath windows, through which the coin may be viewed. After the lapse of a predetermined time, when the machine is 65 again locked against use, the coin may be freed and allowed to pass on to a chute and thence into a coin receptacle out of sight.

Other features and advantages will here- 70 inafter appear.

In the accompanying drawings,

Figure 1 is a sectional side elevation of the coin-operated time-controlled mechanism showing my invention as applied 75 thereto, the device being illustrated as applied to a typewriting machine, the machine being locked against use.

Fig. 2 is the same as Fig. 1 except that the parts are shown as having been just un- 80 locked, the knob for unlocking the machine not having been released by the operator.

Fig. 3 is a front elevation showing the parts in the same position as shown in Fig. 2.

Fig. 4 is a front elevation showing the parts in normal position, a coin being shown in dotted lines, about to enter the machine.

Fig. 5 is a front elevation showing the parts shown in Fig. 3 with the actuating 90 knob and parts returning to normal position, the coin being shown in the act of assuming a visible position.

Fig. 6 is a plan view of the parts as shown in Fig. 5.

Fig. 7 is a front elevation showing the actuating knob returned to normal position, the coin being shown as resting on the coin-chute in visible position, the opening being shown in dot-and-dash lines.

Fig. 8 is a front elevation showing the way the parts operate when a washer is used in an effort to operate the machine.

Fig. 9 is a front elevation showing a disk which was too thick to operate the machine 105 and therefore remained in the actuating parts, the disk being shown as being removed by the insertion of a coin.

Fig. 10 is a perspective view showing the position of the openings through which the coin is visible.

Fig. 11 is a perspective view showing the 5 detent which holds the coin in the actuating parts.

Fig. 12 is a fragmentary perspective view showing the actuating knob and the stop therefor.

10 My invention may be applied to a coin-operated, time-controlled typewriting machine such as illustrated in the patent to Corcoran 990,112, in which the keys 20 of the machine, having hooks 21, are normally held against depression by a bail 22 underlying said hooks. The bail 22 comprises arms 23 and a shaft 24, and is locked beneath the hooks of the keys by means of an arm 25, bearing against one of the arms 23 and 15 rising from the shaft 26. Fixed to the shaft 26 is an arm 27, having a pin 30 to engage a flat portion 29 on a locking bar 28, so as to hold said arm 27 and connected parts against motion, as seen in Fig. 1. The arm 25 and the locking bar 28 being inside the 20 casing 31 of the coin-operated, time-controlled mechanism, can not be moved or operated to unlock the machine except by the insertion of a coin.

25 In order to unlock the machine, the operator first inserts a coin through a slot 32 in the casing. The inserted coin has the effect of acting as an interponent between two parts of the mechanism, one part being connected to an operating knob 33 at the outside of the casing, and the other part being 30 connected to the locking bar 28, so as to cause the knob 33, when turned by the operator, to operate the bar 28 moving the flat portion 29 thereon, away from the pin 30, thereby permitting the arms 25, 27 to be moved to inoperative position by a spring 34, this in turn permits the bail 22 to be 35 moved to ineffective position by a spring 35, thereby unlocking the keys of the machine.

40 After the keys of the machine are unlocked, the bar 28 is latched in inoperative position, and remains so until the lapse of a period of time determined by the time-controlling mechanism.

45 As the bar 28 descends to unlock the keys, a pin 36, on said bar, and a pin 37, on an arm 38, pivoted at 39 and geared to the bar 28 by gearing 40, each release a pawl 41, which is mounted at 42 on a timing plate 43, and which is moved by its spring 44 into engagement with a ratchet wheel 45 fixed to an arbor 46 of a clock-work 47.

50 After having released the pawls 41, the arm 38 and the bar 28 are held in releasing position by an arm 48, pivoted at 49 to the arm 38 and having a stud 50, which, as the bar descends, falls into a notch 51 on the arm 52 on said bar. The arm 48 is then detained 55 in this position by a latch 53, pivoted at

39, and having a notch 54, which falls over a pin 55 on the arm 48 and locks said arm with its stud 50 in the notch 51 on the arm 28.

50 At the expiration of the time during which the machine may be used, a pin 56 on the timing plate 43, which is being rotated by the clock-work, cams a trip-lever 57 pivotally mounted on the arm 48, causing said trip-lever 57, through a pin 58 thereon, to 55 lift up a hooked arm 59 on the latch 53, thereby releasing the arm 48. As the pin 56 continues its camming action, the pin 58 strikes against a lug 60 on the arm 48, and further camming action acts upon the trip-lever 57 and forces the stud 50 out of the 60 notch 51, thereby allowing a spring 61, connected to the arm 38 and the bar 28, to return said arm and bar to their normal positions. The arm 38 and the bar 28, returning 65 to normal position, cause the pins 36 and 37 to engage the ends of the pawls 41, thereby releasing the timing plate from the clock-work; and the bar 28, having a cam portion 62, cams out the pin 30, locking the keys 90 against action. A lug 62^a co-acts with the lug 60 in limiting the movement of the trip-lever 57.

65 In order to inform the operator at the beginning and end of the period of time during which the machine may be used, a bell 63, mounted on the casing by a screw 64, is struck by means of a hammer 64^a loosely mounted on the arbor 46 of the clock-work, and operated by means of a pin 65 on the 100 bar 28, which engages a tappet 66 pivoted to the downwardly-extending arm 66^a of the hammer. The connections between the bell-hammer 64^a and the bar 28 are such that as the bar descends to unlock the keys, 105 the hammer is moved against the tension of the spring 67, and is then released, thus causing the spring to throw the hammer against the bell. The same action takes place at the ascending or locking movement 110 of the bar 28.

115 The coin, in being placed in the machine, is dropped through the slot 32 in the casing 31 and falls into the chute-like slot 69 in a holder 68, in which the coin is temporarily held by a leaf spring 70, fastened to the holder 68 at 70^a. The holder, pivotally mounted on a shaft 71, bearing in the casing 31, is provided with an arm 72, connected by a link 73 to the locking bar 28, so that, as 120 the knob 33 (which is fixed to the shaft 71) is turned, an operating arm 74, also fixed to the shaft 71, strikes against the coin in said holder and rocks said holder, thereby operating the locking bar 28. Thus, it will 125 be seen that the coin, when in the holder, acts as an interponent between the operating knob 33 and the locking bar 28, to cause said arm to operate the locking bar 28 and thereby unlock the keys of the machine for 130

use. If, however, no coin is placed in the machine, the operating arm 74 will move idly past the holder 68, without operating same; the holder being provided with an 5 opening 75 through which the arm 74 may freely pass. After the knob 33 is turned and is released, a spring 76, connected at one end to the operating arm 74 and at the other end to the casing, causes the knob and arm 10 to return to normal position.

In order to prevent the use of a spurious metal disk for operating the machine, the holding spring 70 is provided with a V-shaped notch 77 (Fig. 10), whose sides will 15 not detain a disk thinner than the proper coin, but will only engage and hold a coin of the proper thickness. If the disk used is of less diameter than the proper coin, the spring again will not be effective in detaining the disk in the holder, for if such a disk is used it would pass idly between the wall of the chute-like slot 69 and the spring 70, and out of the holder.

When a good coin of the proper denomination is placed in the holder, and the knob 25 33 is turned, the said holder 68 will be moved with the operating arm 74 until the coin strikes against an arm 78 secured to the casing by screws 79. As the coin and the holder 30 approach this position, as shown in Figs. 2 and 3, the spring 70 is cammed out, so as to release the coin from the holding spring 70 by an arm 80 mounted on the screw 79 and provided with a cam portion 81 which engages the spring 70 as shown in Fig. 6. The coin, however, is held in the holder by frictional engagement with the actuating arm 74 until the knob 33 is released and the spring 40 76 returns the actuating arm. The coin, when thus released, drops upon a tray 82 which assists in guiding the coin to the receptacle 83.

I provide mechanism whereby the coin or disk, which has been used to unlock the 45 machine, may be viewed during the entire period in which the typewriting or other connected machine may be used, so that the person in charge of the machine may, from time to time, inspect the last coin placed in 50 the machines in use.

For accomplishing this, I provide an abutment in the path followed by the coin from the holder 68 to the receptacle 83. This abutment may comprise an upturned portion 84 55 of a chute 85, which co-acts with the tray 82 in guiding the coin. This abutment 84 arrests the coin on the tray directly in front of and beneath openings or windows 86 provided in the casing 31, through which the 60 coin may be viewed. The coin is held in this position during the entire period in which the typewriting or other connected machine may be used, and is released at the close of said period. This may be done by securing 65 the tray to the holder 68, which, by reason

of the connection between its arm 72 and the locking bar 28, is held in operated position until the machine is again locked. As the holder returns to normal position, the tray 70 82 will be lifted above the abutment 84, thus permitting free passage of the coin from the tray 82 to the chute 85, and thence out of sight into the receptacle 83.

Should a person try to unlock the machine by the use of spurious coins, or fail to place 75 any coin in the machine, and make representations to the person in charge of the machine, that a good coin was used but the machine failed to operate, the attendant may easily detect the fraud, for, if a good coin 80 had been used, it would be visible through the windows 86. If there is really a case of fraud, the very absence of the coin from the tray proves it; for if a coin placed in the machine is in any way unfitted to act as an 85 interponent between the actuating arm 74 and the holder 68, (which coöperation is necessary to cause the machine to become usable), said unfit coin, by reason of the fact that the holder has not moved from normal 90 position in which the tray is raised above the abutment and out of sight. The tray 82 may be secured to a hub 87 to which the holder 68 is connected. 95

In order to prevent the use of a washer in an effort to unlock the machine for operation, the part of the actuating arm 74 which strikes the coin is made in the form of a long nose 88, adapted to enter into the hole in the 100 washer; so that when the knob 33 is rotated, the nose 88 of the actuating arm will enter the hole in said washer, and thus fail to move the holder to the position at which it would cause the machine to become usable. 105

As illustrated in Fig. 8, the actuating arm 74 is provided at the base of the nose 88 with a lug or projection 89, adapted to strike the washer after the nose has fully entered the hole in the washer. This is done so as to prevent the washer and nose from becoming caught upon each other. This striking against the washer, although it may cause the holder to be moved, does not cause it to be moved sufficiently to permit the locking 110 115 bar to move to ineffective position.

Should a piece of paper or other fibrous material be inserted in the holder in an effort to operate the machine, the paper being only held by its side edges, would be forced out 120 of the holder by the nose striking in the center thereof, thus preventing the holder from being moved to unlocking position.

Variations may be resorted to within the scope of the invention, and portions of the 125 improvements may be used without others.

Having thus described my invention, I claim:

1. In a coin-operated time-controlled machine, the combination with a temporary 130

coin-holder, of a device for causing said coin to remain in said holder, said device being effective only on coins of a certain thickness, means for releasing said coin from said 5 holder and concomitantly causing the machine to be usable, means upon which the coin is adapted to rest after being released from said temporary holder, means whereby the coin may be viewed, and means operated 10 concomitantly with the mechanism for rendering the machine unusable for causing the coin to pass out of sight.

2. In a coin-operated time-controlled machine, the combination with a casing having 15 a slot through which the coin may be passed, of releasing mechanism, time-controlling mechanism, a holder for receiving the coin, said holder being connected to the releasing mechanism, whereby the machine may be used, and whereby the time-controlling mechanism is put into operation, means associated with said holder for retaining only 20 coins of proper thickness, actuating means controlled by the operator for operating the holder through the coin held therein, and means for releasing the coin from said holder, after the machine has been made 25 usable, and after the time-controlling mechanism has been set in operation.

3. In a coin-operated time-controlled machine, the combination with a casing, of a coin holder within said casing, an actuator for operating said coin holder, means to release the coin from the holder when said 30 holder is actuated, a coin chute within said casing to receive the coin from said holder, said chute comprising two relatively movable parts, one of said relatively movable parts of the coin chute being secured to the 35 holder, an abutment to arrest the coin on the coin chute, means for retaining the holder in actuated position, and means for returning said holder to normal position, said returning action moving said movable 40 part of the coin chute, so as to allow the coin to pass the abutment thereon.

4. In a coin-operated time-controlled mechanism, the combination with a swinging coin-chute, of a spring-detent adapted 50 to retain a coin of proper thickness in the chute, but adapted to permit a disk of less thickness to pass, a handle, an operating arm adapted to be swung by said handle against a coin detained by said detent to swing said chute, and a cam adapted to be struck by said detent when the chute is so 55 swung to cause the detent to release the coin.

5. In a coin-operated time-controlled mechanism, the combination with a swinging coin-holder, of a starting arm, means for detaining said arm in its starting position, connections such that said holder and said arm always move together, a spring-detent adapted to retain a coin of proper 60 thickness in the holder, but adapted to per-

mit a disk of less thickness to pass, a handle, an operating arm adapted to be swung by said handle against a coin detained by said detent to swing said holder to carry said starting arm to starting position, so that it 70 will be detained there and hold the holder where it has been moved, and a cam adapted to be struck by said detent when the holder is so swung to cause the detent to release the coin, thus permitting it to drop when 75 the handle is released.

6. In a coin-operated time-controlled mechanism, the combination with a swinging coin-chute, of a spring-detent adapted to retain a coin of proper thickness in the 80 chute, said detent comprising V-arms adapted to engage the coin to determine whether it is of proper thickness, a handle, an operating arm adapted to be swung by said handle against a coin detained by said detent to swing said chute, operating mechanism, a release for said operating mechanism actuated by said coin when so held, and means for releasing said coin upon release 85 of said operating mechanism.

7. In a coin-operated time-controlled mechanism, the combination with a swinging coin-chute, of a spring-detent adapted to detain a coin of proper thickness in the chute, said detent comprising V-arms 90 adapted to engage the coin to determine whether it is of proper thickness, a handle, a finger connected to said handle and adapted to be moved thereby to strike about the center of a detained coin, so that a perforated washer would permit the finger to pass beyond the proper actuating point, and means adapted to release said detent when the chute is swung by said finger and effective on a coin to move the chute.

8. In a coin-operated time-controlled mechanism, the combination with a swinging coin-chute, of a spring-detent adapted to retain a coin of proper thickness in the chute, said detent comprising V-arms 100 adapted to engage the coin to determine whether it is of proper thickness, a handle, an operating arm adapted to be swung by said handle against a coin detained by said detent to swing said chute, operating mechanism, a release for said operating mechanism actuated by said coin when so held, means for releasing said coin upon release 105 of said operating mechanism, said chute comprising a fixed member relatively to 110 which the swinging chute swings, and an abutment on said fixed member adapted to arrest any coin on the swinging chute which properly has been effective to release the operating mechanism.

9. In a coin-operated time-controlled mechanism, the combination with a swinging coin-chute including a table, of a fixed chute adapted to receive a coin from the swinging chute-table, a spring-detent adapt- 115 120 125 130

ed to retain a coin of proper thickness in the swinging chute, but adapted to permit a disk of less thickness to pass, the swinging chute normally in position to allow a 5 disk thereon to slide on to the fixed chute, a handle, an operating arm adapted to be swung by said handle against a coin detained by said detent to swing the swinging chute, a releasing mechanism connected to 10 move with said swinging chute, and adapted to be held in swung position during a pre-determined time, a lug on said fixed chute adapted to detain a released coin on said

swinging chute-table when in its swung position, and means for releasing said detent 15 when the swinging chute has been swung to make the releasing mechanism effective, thus permitting a coin to be dropped onto the swinging chute-table and to be viewed thereon while the releasing mechanism is 20 effective.

JOHN C. McLAUGHLIN.
